UNITED STATES PATENT OFFICE.

WILLIAM W. HARRIS, OF DETROIT, MICHIGAN.

PRIMING-CUP.

1,339,883.

Specification of Letters Patent.

Patented May 11, 1920.

Application filed January 12, 1918. Serial No. 211,652.

To all whom it may concern:

Be it known that I, WILLIAM W. HARRIS, a citizen of the United States of America, residing at Detroit, county of Wayne, State 5 of Michigan, have invented certain new and useful Improvements in Priming-Cups, of which the following is a specification.

The invention relates to priming cups.

More particularly the invention relates to 10 priming cups for gas and other explosive engines, comprising a body shell having a fluid receiving chamber and a valve seating opening, constructed to be self-centering when in closed position but loosely mounted 15 within the body shell when in open position.

The objects of the invention will be more fully understood from the following description and accompanying drawings, in which—

20 Figures 1 and 2 are respectively side and central elevations of one form of the invention; Figs. 3, 4, and 5 are detail views of parts of the same;

Figs. 6 and 7 are respectively a central 25 elevation and a plan detail view, of a further modification;

Figs. 8, 9 and 10 are respectively a central 30 sectional elevation, detail elevation and top plan view of a still further modification; and

Figs. 11, 12 and 13 are respectively a central sectional elevation, top plan view and a section on line 13—13 of Fig. 11, of a further modification of the invention.

35 Referring to Figs. 1 to 5, inclusive, the priming cup comprises the body shell 1 having the fluid receiving chamber 2 into which the gasoline or other priming fluid is poured. The valve seat 3 is provided at the 40 discharge opening 4, the said valve seat 3 in this form of the invention being shown on the upper face of the sides of the discharge opening 4.

The discharge opening 4 is shown closed 45 by the spindle 5 having the lower portion 6 thereof constructed to serve as the closure. As shown in Fig. 2, the spindle 5 is preferably provided with the reduced pilot portion 18 projecting below the valve-seating 50 opening 4.

The spindle 5 is mounted within the body shell 1 to be loosely retained therein when the spindle 5 is in non-closing position, but to effect self-centering when moved to clos-

ing position. Such object of the invention 55 is attained in the specific form by the provision of the secondary inner shell 7, secured by means of the in-turned flange 8 and co-acting beading 9 to the main body shell 1. Coacting with the secondary shell 7 is an 60 externally threaded plate 10, having lugs 11, 11, adapted to extend through the opening 12, 12 in said secondary shell 7, for retaining said plate 10 in proper relation to the remaining parts. The spindle 5 is threaded 65 externally at 13 to mesh with the internal threads of plate 10.

The secondary shell 7 may be provided with the additional fluid openings 14, 14 for affording sufficient passage for the flow of 70 fluid from the chamber 2 through the lower portion 15, and thence out of the discharge opening 4. The lower portion 15 is threaded 75 at 16 for reception into the opening in the cylinder wall.

The spindle 5 is provided with a suitable 80 manipulating element or portion 17, for opening and closing the valve opening into the engine cylinder, a convenient form of such manipulating means being effected by bending the spindle 5 transversely adjacent its external end, whereby the spindle is precluded from accidentally dropping through the valve opening.

It will be noted that upon opening the 85 valve, by turning the spindle 5, the spindle 5 and plate 10 will be retained loosely within the body shell 1 by reason of the mounting means comprising the secondary shell 7. However, upon closing the valve opening, by 90 reversely turning the spindle 5, the construction of the valve closure portion 6 of the spindle 5 and the assembly of the spindle 5 and plate 10 relative to the secondary shell 7 and main body shell 1 effect self-centering 95 and positioning of the valve closure parts.

Figs. 3, 4 and 5 show in greater detail the constructional features of the secondary shell 7 and the plate 10.

It will be observed that the aforesaid 100 parts of my priming cup are readily manufactured by means of simple stamping machines or a simple lathe, and on the whole presents a relatively simplified manufacturing problem including the question of labor 105 as compared with the ordinary priming cup having an internally threaded, fixed valve closure.

The following additional forms of my invention embody the aforesaid and other advantages.

In the modification shown in Fig. 6, the 5 spindle 5 is closed by downward movement of the same, similar to Figs. 1 and 2, and similarly provided with a reduced pilot portion 18. However, the spindle 5 is in this 10 modification shown in threaded relation with a saddle 23 mounted to normally hang loosely within the body shell 1, as by means of the suspending lugs 24, 24, extending through suitable openings in the body shell 1.

15 In the modification shown in Figs. 8, 9 and 10, the spindle 25 is shown in threaded relation with the internally threaded tube 26, said tube 26 having a depending portion 27 provided with the valve closure 28. These 20 parts are mounted within the body shell 1 by means of the bar 29 having its ends fixed within openings within the casing 1, and passing through a slot in the tube 26. The valve closure 28 is moved to close the discharge opening 4 by upward movement of the spindle tube 26 upon clockwise turning of the spindle 25. The relation of the spindle 25, tube 26 and depending portion 27 when in closed position are shown in Fig. 9, 25 whereby the tube 26 and its depending portion 27 are raised. When the spindle 25 is turned to open the valve, the spindle and its associated parts are loosely held, laterally and longitudinally, within the main body 30 shell 1, to an extent determined by the clearance between the lower end of the spindle 25 and the end of the slot in the tube 26.

The modifications shown in Figs. 11, 12 and 13 comprise an internally terminated 40 spindle 30, threaded externally, and meshing with the internally threaded saddle 31, and normally loosely mounted within the main shell 1 by means of the suspending flanges 32. The spindle 30 is raised to valve-closing 45 position by rotating the saddle 31 by means of its projecting flanges 32, and similarly lowered to valve-opening position by the opposite rotation of the flanges 32. The plate 33, having the enlarged angular recess 34, precludes the spindle 30 from effective 50 rotation. The head or nut 35 serves to prevent the spindle 30 from separating from its support, in the event that the saddle 31 is turned until the head 35 encounters the saddle 31, but even in such circumstance 55 the saddle prevents the spindle and valve from dropping out of the cup proper and the valve proper prevents the spindle from being lifted out of the cup proper. The recess 34 affords passage for the priming 60 fluid and combines with the support 31 to provide the lateral movement of the spindle and attain the aforesaid objects of the previously described modifications of my invention. When the saddle 32 is turned to open 65

the valve 36, the spindle is loosely retained laterally within the cup proper, and also loosely retained longitudinally dependent upon the extent of opening of the valve.

In the form of the invention shown in 70 Figs. 1 to 5, inclusive, the limited vertical and lateral movement of the spindle and nut is provided under the condition of opening of the valve, by the loose fit of the lugs 11, 11, within the openings 12, 12, in the form 75 of the invention shown in Fig. 6. Similar limited vertical and lateral movement of the spindle and nut is provided for by the loose fit of the lugs 24, 24, within the openings in the shell 1. Similarly, in the form shown 80 in Fig. 11, limited vertical and lateral movement of the stem and the saddle 31 threaded therewith is provided by the clearance between the edges of the recess 34 and the faces of the reduced portion of the spindle 30 and 85 the suspending flanges 32 above the upper edge of the shell afforded when the valve is in open position.

It will be further noted that the lateral 90 movability of the spindle and valve closure 95 arrangement of my invention and the self-centering characteristics under closed conditions afford the further advantage of self-adjustment upon wear of the parts. The self-centering characteristics of the invention are also advantageous in obviating the necessity of absolute perfect fitting in construction or assembly, or in the event of bending or otherwise mis-shaping the parts 100 incident to use.

Whereas I have described my invention by reference to specific forms thereof, it will be understood that many changes and modifications may be made without departing from the spirit of the invention, as defined 105 by the appended claims.

I claim:

1. A priming cup for gas engines, comprising a body shell constructed interiorly to provide a fluid receiving chamber, said body shell being constructed at its top to provide a fluid receiving opening, said body shell being further constructed at its bottom to provide a coöperating discharge opening, two substantially accurately inter-threaded 110 members, means for loosely retaining the said threaded members within said body shell, said retaining means being open to provide for fluid passage therethrough and means on one of said members forming a 115 closure for said discharge opening.

2. A priming cup for gas engines, comprising a body shell constructed interiorly to provide a fluid receiving chamber, said body shell being constructed at its top to provide 120 a fluid receiving opening, and said body shell being constructed at its bottom to provide a coöperating discharge passage, a valve seat coöperating with said discharge 125 passage, an externally threaded member, an 130

- internally threaded member in substantially accurate threaded relation with said externally threaded member, means for loosely retaining one of said threaded members 5 within said body shell, said retaining means being constructed to provide for fluid passage therethrough, and a closure for said valve-seat disposed on one of said threaded members.
- 10 3. A priming cup for gas engines, comprising a body shell constructed interiorly to provide a fluid receiving chamber, said body shell being constructed at its top to provide a fluid receiving opening, said body shell 15 being constructed at its lower portion to provide a fluid discharging passage, a valve seat coöperating with said fluid discharging passage, a threaded member, a valve closure coöperating with said valve seat disposed on 20 said threaded member, a second threaded member in substantially accurate threaded relation with said first named threaded member and means for loosely retaining the said threaded members within said body shell, said retaining means being constructed 25 to permit a limited radial movement relative to said body shell and provided with an opening for the passage of fluid therethrough.
- 30 4. In a priming cup for gas engines, the combination of a cup shell, constructed interiorly to provide an inner fluid receiving chamber, said cup shell being constructed at its top to provide a fluid receiving inlet, said 35 cup shell being further constructed at its bottom to provide a coöperating fluid discharge passage, a self-centering valve coöperating with said discharge passage and valve actuating mechanism comprising two 40 substantially accurately co-threaded members, means for actuating one of said threaded members and means for loosely retaining the other of said threaded members within said cup, said retaining means being provided with an opening for the passage of fluid therethrough, said retaining means being 45 constructed to provide for compensating lateral movement relative to said cup shell.
5. In a priming cup for gas engines, the 50 combination of a body part constructed interiorly to provide a fluid receiving chamber, said body part being constructed at its upper portion to provide a fluid receiving opening, said body part being further constructed at its lower portion to provide a coöperating fluid discharge opening, a valve seat disposed at said discharge opening, a self-centering valve member disposed within 55 said body part, said valve member comprising a closure for said valve-seating opening and including a reduced pilot portion adapted to project through said discharge opening.
6. A priming cup for gas engines comprising a body shell having a fluid receiving 60
- chamber and a valve seating opening with a passage therebetween, an internally threaded member, a secondary inner shell loosely retaining the said member within said body shell, means for securing said secondary inner shell to said body shell, an externally threaded spindle coöperating with said internally threaded member, the lower part of said spindle forming the valve closure for said valve-seating opening when moved into 70 engagement with the upper side thereof, said internally threaded member and said externally threaded spindle having a lateral movement relative to said body shell to an extent sufficient to effect perfect alinement 75 of said valve closure with said valve-seating opening.
7. A priming cup for a gas engine comprising a body shell, having a fluid receiving chamber and a valve-seating opening 80 with a passage therebetween, a secondary shell secured within said body shell, an internally threaded member loosely mounted on said secondary shell, an externally threaded spindle coöperating with said internally 85 threaded member, the lower part of said spindle forming a valve closure when moved into engagement with said valve seating opening, said internally threaded member and said externally threaded spindle having 90 a lateral movement relative to said body shell to an extent sufficient to effect alinement of the valve closure with said valve-seating opening, said spindle further having a reduced pilot portion disposed below said valve 95 closure portion and projecting through said valve-seating opening when in closed position.
8. A priming cup for gas engines, comprising a body member having a fluid receiving chamber and a valve-seating opening with a passage therebetween, said body member being further provided with one or more openings, an internally threaded member, one or more lugs on said member and 100 projecting into said one or more openings for retaining said threaded member within said body member, an externally threaded spindle coöperating with said internally 105 threaded member, the lower part of said spindle forming a valve closure when moved downwardly into engagement with the side of said valve-seating opening, said internally threaded member and said externally threaded spindle having a lateral movement 110 relative to said body member sufficient to effect perfect alinement of said valve closure part with said valve-seating opening.
9. A priming cup for gas engines, comprising a body shell having a fluid receiving 115 chamber, and a valve-seating opening with a passage therebetween, said body shell further having one or more openings, an internally threaded member, lugs on said member projecting into said one or more 120
- 125
- 130

openings for retaining said member within said body shell, an externally threaded spindle coöperating with said internally threaded member, the lower part of said 5 spindle forming a valve closure when moved into engagement with a side of said valve-seating opening, said internally threaded member and said externally threaded spindle having a lateral movement relative to 10 said body shell sufficient to effect perfect alignment of said valve closure part with said valve-seating opening, said spindle having further a reduced pilot portion disposed below said valve closure part and 15 projecting through said valve seating opening when said spindle is in closed position.

10. A priming cup for gas engines, comprising a body shell formed to provide a fluid receiving chamber and having an upper 20 receiving opening and a lower valve-seating opening, two threadedly connected members within said body shell, means for loosely retaining said members, said retaining means being open to provide for fluid 25 passage and means on one of said members forming a closure for said valve-seating opening, said one member further being provided with a reduced pilot portion projecting below said valve-seating opening.

30. 11. A body shell constructed interiorly to provide a fluid receiving chamber and at its upper portion to provide a coöperating fluid inlet and at its lower portion to provide a coöperating fluid discharge, a closure for 35 said discharge, a stem controlling said closure, said stem having a portion provided with screw-threading, and means for mounting said stem within said body shell to provide limited lateral movement of said stem, 40 said means including an element having a screw-threaded portion in substantially accurate screw-threaded relation with the screw-threading of said stem portion.

12. A body shell constructed interiorly to 45 provide a fluid receiving chamber and at its upper portion to provide a coöperating fluid inlet and at its lower portion to provide a coöperating fluid discharge, a closure for said discharge, a stem controlling said 50 closure, said stem having a portion provided with exterior screw-threading, an element provided with interior screw-threading in substantially accurate threaded relation with the screw-threading of said stem and 55 means for mounting said element within said body shell to provide limited lateral movement of said element.

13. In a priming cup structure, the combination of a cup body having an outlet at 60 its lower end, a valve stem extending axially through said body, a valve for said outlet controlled by said stem, said stem having a threaded section, and a nut receiving said threaded section and confined within said body against rotation but with limited free-

dom of lateral movement whereby to permit said stem and valve to coöperate to accurately close said outlet.

14. In a priming cup structure, the combination of a cup body having an outlet at 70 its lower end, a valve stem extending axially through said cup body, a valve coöperating with said stem to control said outlet, said stem having a threaded section, a nut member receiving said threaded section, and 75 means for locking said nut member against rotation but permitting limited lateral and vertical movement thereof during turning of the stem whereby said stem and valve may coöperate to accurately fit and close 80 said outlet.

15. In a priming cup structure, the combination of a cup body having an outlet at 85 its lower end, a valve stem extending axially through said cup body, a valve coöperating with said stem to control said outlet, said stem having a threaded section, a nut member receiving said threaded section, and abutments on said cup body for locking said nut member against rotation and against all 90 but limited vertical and lateral movement whereby when said stem is turned it may move laterally to insure accurate alignment of the valve with said outlet.

16. In a priming cup structure, the combination of a cup body having an outlet at 95 its lower end, a valve for controlling said outlet, a stem for said valve extending upwardly through said cup body and having a threaded section, a nut member within 100 said cup body receiving said stem, and means for preventing extended rotation of the nut member, there being just sufficient clearance between said nut member and the walls of said cup body to permit only limited 105 freedom of movement of said nut member when said stem is turned whereby said stem is free to align itself to assure accurate coöperation of said valve with said outlet, the nut member being cut away to 110 permit the passage of priming fluid.

17. In a priming cup structure, the combination of a cup body comprising a cup-shaped top section, a polygonal intermediate section of reduced width and a threaded 115 end for engaging in a threaded opening, the lower wall of said end having an outlet passageway therethrough, a valve for said outlet passageway, a supporting stem for 120 said valve extending axially through said cup structure sections, the intermediate part of said stem being threaded, and a nut member within said cup structure receiving said threaded stem, said cup structure coöperating with said nut member to prevent extended 125 rotation of said nut member, there being sufficient clearance between said nut member and cup structure walls to permit limited lateral and vertical movement of the nut member when the stem is turned where- 130

by said stem is sufficiently free to aline itself and cause accurate coöperation of such valve with said outlet.

18. In a priming cup structure, the combination of a cup body comprising a top section, a polygonal intermediate section, and a threaded end, the lower wall of said end having an outlet passageway, a valve for controlling said passageway, a stem for 10 said valve extending upwardly through said cup body and having a threaded section, a nut member within said cup body receiving said threaded stem, said cup structure co-operating with said nut member to prevent 15 extended rotation of said nut member, there being just sufficient clearance between said nut member and cup body sides to permit limited lateral movement of said nut member when the stem is turned, and abutments 20 on said cup body for allowing limited vertical movement of the nut member, such limited movements of the nut member permitting said stem to automatically aline itself when turned and to insure accurate co- 25 operation of said valve in said outlet.

19. In a priming cup structure, the combination of a cup body comprising a cup-shaped top section, a polygonal intermediate section of reduced width and a threaded end 30 for engaging in a threaded opening, the lower wall of said end having an outlet passageway therethrough, a valve for said outlet passageway, a supporting stem for said valve extending axially through said cup 35 structure sections, the intermediate part of said stem being threaded, and a nut member within said cup structure receiving said threaded stem; said cup structure coöperating with said nut member to prevent ex- 40 tended rotation of said nut member, there being clearance between said nut member and cup structure walls for the flow of fluid.

20. In a priming cup, the combination of a body structure formed to provide a fluid 45 receiving chamber having an open end and a valve seating discharge opening, a valve closure for said opening, means for actuating said valve closure and means permitting a vertical and lateral self-centering adjust- 50 ment of said valve closure in relation to

said valve seating opening when the said valve closure is actuated to the closed position.

21. In a priming cup, the combination of a body structure comprised of two shells 55 formed to provide a fluid receiving chamber having an open end and a valve seating discharge opening, a valve for said discharge opening comprising an externally threaded actuating stem extending axially 60 through said body structure, a nut member coöperating with said stem, said nut member being loosely retained between sections of the two said shells thereby providing for the limited movement in all directions and 65 means on one of said shells coöperating with means on said nut member to prevent the extended rotation thereof.

22. In a priming cup, the combination of a body comprised of two interlocking shells 70 formed to provide a fluid receiving chamber having an open end and a valve seating discharge opening, one of said shells being externally formed to provide a wrench seating section and a threaded section, a 75 valve for said discharge opening comprising an externally threaded actuating stem extending axially through said body structure, a nut member coöperating with said stem, said nut member being loosely re- 80 tained between sections of the two said shells thereby providing for its limited movement in all directions and means on one of said shells coöperating with means on said nut member to prevent the extended 85 rotation thereof.

23. In a priming cup, the combination of a body structure formed to provide a fluid receiving chamber having an open end and a valve seating discharge opening, a valve 90 closure for said opening, means for actuating said valve closure and means permitting a lateral self-centering adjustment of said valve closure in relation to said valve seating opening when actuated to the closed 95 position.

In testimony whereof I have signed this specification this 2nd day of January, 1918.

WILLIAM W. HARRIS.
